UNITED STATES PATENT OFFICE.

FRANK C. KRONAUER, OF PATERSON, NEW JERSEY.

ELECTRICAL RESISTANCE INSTRUMENT.

Application filed February 12, 1925. Serial No. 8,852.

My invention relates to electrical resistance instruments of the kind used in radio and similar electric circuits, and the object of my invention is to provide a variable resistance instrument that admits of easy and accurate control and adjustment of high resistances.

I accomplish this object by means of the instrument described in this specification and illustrated in the attached drawing that forms a part of this specification. In this drawing, Fig. 1 shows a view of the instrument, disclosing the variable resistance features and its construction; Figure 2 is a cross section taken along the line 2—2 of Fig. 1. Figure 3 is a longitudinal section of the connecting sleeves S and S' of Fig. 1, showing the method of inserting the container tubes T and T'. Figure 4 is a longitudinal section of a fragment of the container tube T and shows a conductor pin Y sealed into the tube T. Similar letters refer to similar parts throughout the several views.

The container tubes, T and T', each forming an arc of a circle, are constructed of any good insulating material suitable for the purpose, preferably glass. These tubes are joined by the metallic sleeves S and S'. The depressed ring t of the sleeves S and S' prevent the tubes T and T' from making contact, and provide two metallic segments in the interior of the tubular container ring, S, T', S', T. This container ring is attached to the insulating support B by the clips C and C'. These clips afford electric contact between the sleeves S and S' and the binding posts P and P' respectively. The support B is secured to turn with the shaft F in the bearing K which is inserted in the supporting panel D. The usual type of radio instrument dial I is attached to the shaft F to facilitate operation of the instrument.

During the process of manufacture a quantity of mercury, M, is introduced into the container tube T T'. This mercury occupies about one third of the volume content of the entire container ring. The container ring is then filled very nearly full with a suitable fluid resistance R, the specific gravity of which is less than that of the mercury. The tube is then sealed to form a continuous ring as illustrated. The mercury M falls to the lower section of the container ring, while the fluid resistance R, which for high resistances is preferably some form of refined mineral oil, of suitable and selected conduc-

tivity, rises above the level of the mercury, as illustrated in the drawing. Electrical contact with the mercury M and the fluid R is maintained through the sleeves S and S' respectively, and so through the binding posts P and P' that form the electrical terminals of the instrument.

While S and S' are, with respect to the level L of the mercury M, in the position shown in solid lines in Fig. 1, the electrical resistance of the instrument is maximum, since the conductivity of the fluid R is very much smaller than that of the mercury M. If we now rotate the container tube and its support B on the shaft F, in the direction of the arrow W, to the position shown in dotted lines in Fig. 1, the resistance of the circuit P S R M S' P' has decreased, since the distance from the contact S to the level L of the mercury M has decreased, while S' continues to make contact with the mercury M. In other words the resistance of the instrument has been reduced by this setting. We can continue to rotate the ring container and its support in the direction of the arrow W until the contact S very nearly touches the mercury M. At this point while still retaining the fluid R in the circuit, the minimum resistance of the circuit P R M P' will be found.

It will be seen that in this manner a smooth variation in resistance can be obtained by a partial rotation of the instrument about its axis, provided that the instrument is mounted with the tubular ring container S T' S' T in a vertical or nearly vertical plane.

In use, suitable flexible wire connectors, not shown, are connected to the terminal posts P and P', to connect the instrument to other parts of a circuit. It is of course not necessary that the tubular ring container be formed to a truly circular ring, but this form is desirable for uniformity of operation and appearance. To simplify construction, a conductor pin Y shown in the fragmentary view Fig. 4, can be sealed into or through the tube T, substituting for the contact S or S'.

The face X of the dial I has suitable graduations common to radio instrument dials. The sleeves S and S' can, if desired be constructed of other conducting material than metal. Carbon can be used for this purpose.

The change in resistance in the type of instrument hereinbefore described will not de-

crease directly in proportion to a decrease in the distance between S and L. This is due to the conductivity of the fluid R between S and L', Fig. 1. When using mercury for the fluid M and a high resistance fluid for R, the resistance of the mercury column can be neglected for practical purposes. The divided circuit resistance for any position of S and S' can be computed for the circuit of resistances in parallel, S L S', and S L' S', in the well known manner.

If it is desirable to have the resistance of the instrument vary in proportion to the distance between S and the surface L, mercury is preferably used for the fluid M and a high resistance fluid for R. Then, during the process of manufacture, the level of R is raised only to the line 1', Fig. 1. When so constructed the range of the instrument will be limited to a movement of contact S between the radial lines A—A' Fig. 1.

It will be seen from the foregoing that the principle of my invention consists essentially of the use, in a circuit, of two fluid conductors of unlike conductivity and specific gravity, that at their surfaces of contact form closed points in the circuit, together with means for varying the electrical lengths of the said fluids in the circuit. A plurality of fluids may be substituted for the fluid R, if desired.

The instrument illustrated and described in these specifications embodies this principle in a convenient and useful manner, but his instrument can be constructed differently without departing from the spirit of my invention, and I do not wish to limit the scope of my invention to the details and features of construction shown and described in these specifications.

I claim as new and desire to secure by Letters Patent the following:

1. In a variable resistance instrument, the combination of two fluid conductors that

differ in conductivity and specific gravity, means for making electric contact with each of the said fluids separately, and means for varying the positions of the said contacts with respect to the relative positions of the said fluid conductors.

2. In a variable resistance instrument, the combination of two fluid conductors that differ in specific gravity and conductivity, means for maintaining each of the said fluids as individual sections of an electric circuit of which the said instrument forms a part, means for keeping a portion of the surface of each of the said fluids in contact with a portion of the surface of the other fluid, means for making variable points of electric contact with each of the said fluid conductors separately, and means for varying the positions of the said variable points of contact, with respect to the positions of the contacting surfaces that join the two fluids.

3. A variable resistance instrument, in which an insulating container that contains two fluid conductors differing in conductivity and specific gravity, is mounted to rotate about an axis, and to vary with the said rotation, the positions, with respect to the said fluids, of conducting contacts that make contact with each of the said fluid conductors separately.

4. In a variable resistance instrument, the combination of a plurality of fluid conductors differing from one another in conductivity and specific gravity, an insulating container inclosing the said fluid conductors, means for making separate electric contacts between the said fluid conductors and a circuit external to the said insulating container, and means for varying the positions of the said contacts with respect to the relative positions the said fluid conductors have to one another.

FRANK C. KRONAUER.
